UNITED STATES PATENT OFFICE.

ALBION L. WARNER, OF NEW YORK, N. Y., ASSIGNEE TO CHARLES LYON RUSSELL, OF RAHWAY, NEW JERSEY.

FOLDING TABLE.

Application filed November 24, 1926. Serial No. 150,435.

The object of this invention is to provide a table having a folding top, which is adaptable for the refectory type of table now so commonly used in tea rooms and breakfast nooks. The table when the top is in its closed position presents somewhat the appearance of a colonial type of folding top table. When the top is opened out, however, the longitudinal direction of the two leaves or sections is parallel to their original position and parallel to the length of the frame rather than occupying a position of right angles to the closed position as in the colonial type.

The accompanying drawing shows one practicable embodiment of my invention, in which drawings,

Figure 1 is a front view partly in section of the table.

Fig. 2 is a cross sectional view of the table shown in a closed position, and

Fig. 3 is a similar view showing the open position.

The base of the table will be of such convenient form as is indicated by its intended use. In the illustration there is shown a leg, 5, at each end, these being connected to pedestals, 6, and the end pedestals are connected by a longitudinal member, 7. The legs, 5, at the respective ends are connected to cross members, 8, which are fastened to the front and back frame, or valance members, 9—10, of the table top. These front and back frame members are shown extending longitudinally of the table and connected together at the ends by frame or valance members, 11. The upper ends of the legs are also shown connected by a longitudinally disposed brace, 12.

The table top proper constitutes two leaves, 13 and 14, hinged together at, 15, which for convenience will be called the back of the table. The lower member, 13, rests on the valances when either in its opened or closed position. The end valances, 11, are shown furnished with guides for the table top; in the present illustration strips of wood, 16, located near the top and cooperating with rabbeted blocks, 17, secured to the underside of the lower leaf member, 13.

When it is desired to open the table, assuming it to be in the Fig. 2 position, the operator draws the folded leaves toward the front until the edges carrying the hinges, 15, assume a medial position; the upper leaf section, 14, is then opened out into the Fig.

3 position. It is quite apparent that unless considerable care is exercised in moving the leaves either to the opening or closing position that the guide members, 17, will cramp on the guides, 16. Or if these are sufficiently loose to permit free movement, the leaves will assume an angular, or skewed, position relatively to their desired final position. For the purpose of steadyng the leaves in this movement from back to front and from front to back, and for compelling the parts to move in right lines, I have provided a guide linkage consisting of a pair of boards, 18 and 19, of substantial length in respect of the length of the table. These boards are shown hinged together at, 20—20, and the board, 18, hinged at, 21—21, to the lower side of the front frame or valance member, 9. The board, 19, is shown hingedly connected to the lower side of the leaf, 13; in the present instance there being a cleat, 22, of sufficient length secured to the underside of the leaf, 13, to the underside of which cleat the hinges, 23—23, which are fastened to the other edge of the board, 19, are secured. The hinges of the several pairs are shown located at a sufficient distance apart to afford the proper leverage for imparting the desired lateral rigidity to the linkage system.

It is quite obvious that if a sufficient number of hinges are used and placed at sufficiently wide distances apart this linkage system will of itself be sufficient to guide the leaves in a right line movement from front to rear. The guides, 16 and 17, serve more the purpose to take up strains arising when pressure is exerted longitudinally of the table and also to hold the leaf, 13, against any tendency to rise, not only while it is being moved, but also when the table is lifted by the leaves or when the leaves are opened out in the full table position and weight is applied to the free and otherwise unsupported edges.

As a convenient means for holding the table in the full leaf or extended position represented in Fig. 3, I have illustrated a thin strip of wood, 24, pivoted to the underside of the leaf, 13, and of such length that when the leaf, 13, is in its fully opened position, this brace will engage the inner side of the back framing member, 10.

When it is desired to close the table the leaf, 14, will be folded forward over the

leaf, 13, which will expose the brace, 24, so that this may be turned upon its pivot shown in the form of a screw, 25, and turned out of the way, thereupon the leaf, 13, will be moved to its full backward position, this motion being guided and permitted by the steadyng links, 18 and 19. When it is again desired to open the table the folded leaves will be shifted forward and the brace, 24, brought into a convenient position for the hand of the operator by means of a chain, 26, connected to the end of the brace and to the frame of the table.

Although but one embodiment of the invention is shown in the illustration, it will be apparent that various changes may be made within the scope of the claims without departing from the spirit of the invention.

Having described my invention I claim and desire to secure by Letters Patent:

1. In a folding table, the combination with a frame, of a pair of leaves hinged together and supported thereon and a pair of rigid links pivoted together and to one of the leaves and frame for preventing skewing of the leaf.

2. A table comprising a base having a frame or valance, a top resting upon the upper edge of the frame and adapted to

move transversely thereof, and a leaf pivoted to the edge of the top and adapted to open and close upon the said top, the end members of the frame being provided with guides and the lower side of the table top being provided with mating guides, and a pair of rigid links pivoted together and to the underside of the table top and to the frame or valance for preventing skewing of the table top in its transverse movement.

3. A table comprising a base having a frame or valance, a top resting upon the upper edge of the frame and adapted to move transversely thereof, and a leaf pivoted to the edge of the top and adapted to open and close upon the said top, the end members of the frame being provided with guides and the lower side of the table top being provided with mating guides, and a pair of boards extending longitudinally of the table, one of said boards being pivoted to the underside of the top and the other board to the frame or valance, the other edges of said boards being pivoted together for preventing skewing of the top when shifted transversely of the table.

Signed at New York, N. Y. this 18th day of November, 1926.

ALBION L. WARNER.
